UNITED STATES PATENT OFFICE.

ARTHUR S. ALEXANDER, OF NEW YORK, N. Y., ASSIGNOR TO THE J. ALEXANDER MANUFACTURING COMPANY, OF NEW YORK, N. Y., A CORPORATION OF NEW YORK.

DESIGN FOR A BEZEL.

58,126.

Specification for Design. Patented June 14, 1921.

Application filed December 13, 1919. Serial No. 344,664. Term of patent 14 years.

To all whom it may concern:

Be it known that I, ARTHUR S. ALEXANDER, a citizen of the United States, residing in the city of New York, county and State of New York, have invented a new, original, and ornamental Design for a Bezel, of which the following is a specification, reference being had to the accompanying drawing, forming a part hereof.

In the drawing,—

Figure 1 is a front view of a bezel for a mirror showing my new design.

Fig. 2 is a section through Fig. 1.

I claim:

The ornamental design for a bezel, substantially as shown.

ARTHUR S. ALEXANDER.
